UNITED STATES PATENT OFFICE.

MICHAEL J. REYNOLDS, OF WEST HAVEN, CONNECTICUT, ASSIGNOR TO STROUSE ADLER & CO., OF NEW HAVEN, CONNECTICUT, A FIRM COMPOSED OF ISAAC M. ULLMAN AND LOUIS M. ULLMAN, OF NEW HAVEN, CONNECTICUT, AND GEORGE MEYER, OF NEW YORK, N. Y.

COMBINED CORSET AND BRASSIÈRE.

Application filed December 13, 1924. Serial No. 755,679.

To all whom it may concern:

Be it known that I, MICHAEL J. REYNOLDS, a citizen of the United States, residing at West Haven, in the county of New Haven and State of Connecticut, have invented a new and useful Improvement in Combined Corsets and Brassières; and I do hereby declare the following, when taken in connection with the accompanying drawings, and 10 the characters of reference marked thereon, to be a full, clear, and exact description of the same, and which said drawings constitute part of this application, and represent, in—

Fig. 1 a perspective, front view of a combined corset and brassière embodying my invention, and shown in the general position which it would assume on the figure of the wearer.

Fig. 2 a similar, rear view thereof.

Fig. 3 a reverse, plan view of the garment.

My invention relates to a combined corset and brassière, the object being to produce a simple, convenient, comfortable and effective garment of the character described.

With these ends in view, my invention consists in a combined, side-opening corset and brassière, characterized by a pair of symmetrical, externally-applied, non-elastic, abdomen-supporting flaps applied to the front of the corset, over a centrally-arranged elastic gusset set thereinto, and lacing on the median line of the corset.

My invention further consists in a combined corset and brassière having certain details of construction as will be hereinafter described.

In carrying out my invention, as herein shown, I employ a shaped corset-body 5 of non-elastic material, having the center of its front-section provided with an elastic gusset 6 extending from its lower edge upward to a point substantially about two-thirds of the vertical height of the front of the garment, 40 though this point may vary without departing from my invention. Over the upper portion of the said gusset, I locate a pair of non-elastic, abdomen-supporting flaps 7, the out-

er edges of which are secured to portions of the corset-body, while their inner edges are 50 provided with hooks or eyelets 8 for the reception of lacings 9 by which the wearer supplements the constricting and supporting action of the gusset 6.

As shown, the corset-body is provided 55 with hooks 10 and eyes 11 respectively applied to one edge of its said front-section, and to the forward edge of one of its side-sections, so that the garment is hooked and unhooked to one side of its median front 60 line.

Substantially, so much of the upper portion of the garment as extends above the upper edge of the said abdomen-supporting flaps 7 constitutes its brassière feature and 65 imposes no substantial constriction upon the body of the wearer, this brassière portion, which is under no considerable amount of tension, being held up by shoulder-straps 12.

As shown, also, the lower portion of the 70 garment is provided on either side of the rear-section with elastic gussets 13.

I claim:

A combined, side-opening corset and brassière having a shaped body-portion, an elastic gusset located in the center of the front thereof, and extending from the lower edge of the garment well above its center, a pair of non-elastic, abdominal-supporting flaps superimposed upon the front of the corset 80 and secured to it by their outer edges on either side of the said gusset over which they extend, the upper portion of the garment extending above the said flaps in position to serve as a brassière, means for lacing the said 85 flaps to increase the supporting effect of the gusset, and means to one side of the gusset for securing the ends of the body-portion together.

In testimony whereof, I have signed this 90 specification in the presence of two subscribing witnesses.

MICHAEL J. REYNOLDS.
